UNITED STATES PATENT OFFICE

172,934

LUNCH BOX

Ronald E. Morrah, New York, N. Y.

Application March 5, 1954, Serial No. 29,369

Term of patent 3½ years

(Cl. D58—12)

To all whom it may concern:

Be it known that I, Ronald E. Morrah, a citizen of the United States, residing at New York, in the county of New York and State of New York, have invented a new, original, and ornamental Design for a Lunch Box, of which the following is a specification, reference being had to the accompanying drawing, forming part thereof.

Figure 1 is a perspective view of a lunch box, showing my new design;

Figure 2 is a perspective view of the interior of the box in open position; and

Figure 3 is a group perspective view of the same in its open position.

The dominant features of my design reside in the portions shown by full lines.

I claim:

The ornamental design for a lunch box, as shown and described.
